EXPLOSIVE

Alpheus M. Ball, Wilmington, Del., assignor to Hercules Powder Company, Wilmington, Del., a corporation of Delaware

No Drawing. Filed Apr. 22, 1959, Ser. No. 808,005

7 Claims. (Cl. 52—5)

This invention relates to the art of explosives and more particularly to a new type of explosive composition and to the production of explosive articles therefrom.

As is well known, the properties of commercial explosives require some sort of package for the explosive as ultimately utilized. For example, propellants or low explosives are usually packaged in metallic cartridges, primary explosives are usually packaged in metallic tubes or shells to form initiating devices, and dynamite and other high explosives are usually packaged in paper containers. The constituents chosen to give an explosive for a specific use may be selected from the classes listed above and may be suitably formulated to obtain the characteristics desired for the specific use. However, in general, a package or container is required and these may vary in size from a small cartridge or initiating device to an extremely large shell for large size dynamite cartridges. The purpose of the container may be multifold. It may serve as a receptacle for the explosive alone or receive additional components, provide waterproofness, confinement, ease of handling, etc.

It has now been discovered that it is possible to obtain explosive compositions having the property of being self-contained, thereby eliminating the necessity of containers, and that these explosive compositions are capable of being modified to cover a variety of explosive uses.

In accordance with the present invention such explosive compositions are produced by the formation of the polymerization product of a uniform mixture of polymerizable vinyl material and nonaromatic explosive material, selected from the group consisting of azides, organic nitrates and organic nitramines, the polymerization reaction taking place in situ. Depending on the amount and type of explosive material employed, the polymerization products thus formed may be either combustible or detonatable or both. Depending on the particular polymerizable material employed, the polymerization products will range from flexible, rubbery substances to hard, horny bodies. In any event, all explosive articles of the compositions of the invention will be free from detrimental volatile substituents as compared to prior art compositions wherein volatile solvents generally have been used in the preparation of explosive or combustible charges.

The following examples illustrate various methods of carrying the invention into practical effect.

EXAMPLE 1

Preparation of propellant

The following composition was mixed and poured into molds with removal of entrained air.

	Weight percent
Triton X-100 ¹	0.32
Laminac 4134 ²	3.16
Diallyl phthalate	28.10
Luperco ATC catalyst ³	1.26
Cyclonite (through 60, on 80 mesh)	67.16
	100.00

¹ A condensation product of ethylene oxide with diisobutyl phenol.

² A liquid polyester resin curing to a flexible form.

³ A paste of 50% benzoyl peroxide with tricresyl phosphate as extender.

2

The propellant was then polymerized and cured in situ at 145° F. for 2 days and at 185° F. for 2 additional days. After cooling, the propellant was removed from the molds and potted with a high temperature resistant inhibiting composition and each of the inhibited grains was then cured. The inhibiting composition was identical to the propellant composition with the exception that an inert material (K_2SO_4) was utilized in lieu of the cyclonite.

10 The single-end burning grains thus formed were fired in a 4-inch diameter heavy chambered motor. The propellant in each grain measured $2\frac{1}{2}$ inches in diameter and 4 inches in length. The following results were obtained on each of four grains.

15

	Grain			
	1	2	3	4
20 Nozzle diam. (in.)	0.052	0.055	0.059	0.063
Avg. pressure (p.s.i.)	2,459	1,561	817	792
Avg. burning rate (in./sec.)	0.169	0.121	0.088	0.076

25

EXAMPLE 2

Preparation of high explosive

A benzoyl peroxide catalyst (0.006 g.) was dissolved in 3 g. méthyl méthacrylate, and 10 g. of pentaerythritol tetranitrate added to the solution. The mixture was stirred until the pentaerythritol tetranitrate was thoroughly wet and then sufficient of the mixture was placed in a 6-inch length of 0.30-inch inside diameter glass tubing to fill it to a length of 5 inches. The mixture was packed down lightly with a rod taking care to wet the tube sidewalls thoroughly. The tube was sealed at both ends tightly with corks wrapped in aluminum foil and placed in an oven at 50° C. for 16 hours. After curing was completed, the charge was cooled and the sample freed. A no. 6 E.B. cap was attached to the end of the column with tape and shot. The cured polymer-explosive charge detonated completely with a 7065 m./sec. detonation velocity.

35

EXAMPLE 3

Preparation of flexible fuse

40 45 The following composition was mixed and charged into an 8-inch length of $\frac{1}{4}$ inch inside diameter, thin-walled cellulose acetate tubing:

	Weight percent
Pentaerythritol tetranitrate	60
Nitroglycerin (0.75% ethyl centralite added)	24
Monomeric methyl methacrylate (0.5% benzoyl peroxide added)	12
Polymethyl methacrylate	4
	100

55

The finely-ground polymethyl methacrylate was put into solution with the monomeric methyl methacrylate, and then the remaining ingredients mixed together. The charge was cured at 60° C. for 20 hours. The tubing was stripped from the charge, and the bare fuse was found to be rubbery and flexible. A six-inch length was primed with an Army Engineers' Special E.B. cap and placed on a lead plate. Upon firing the cap, examination of the dent in the lead plate indicated the fuse detonated completely.

EXAMPLE 4

Preparation of shaped charge

60 65 70 A mixture of 60 g. cyclonite and 18 g. styrene-modified polyester, catalyzed with 1% tertiary butyl hydroperoxide, was packed into a 100-cc. glass beaker (approx.

1½ inches diameter x 2½ inches deep). A copper cone made of $\frac{1}{16}$ inch sheet, having a base of 1½ inches and a height of 1½ inches was forced down into the mixture (vertex down) until the level of the explosive-monomer mixture was even with the base of the cone. The charge was cured at 60° C. for 16 hours, and then removed from the glass mold. The charge was primed with a No. 6 E.B. cap, and the base placed two inches above (stand-off distance) a series of steel plates. Upon detonation the jet from the shaped charge made a 3½ inch deep hole in the steel plates.

EXAMPLE 5

Preparation of high explosive charge

A mixture of 70% by weight pentaerythritol tetrinitrate and 30% by weight of a styrene-modified polyester (containing 1% methyl ethyl ketone peroxide), where the styrene-polyester was composed of 30% styrene and 70% of the reaction product of 7.5 moles maleic anhydride, 2.5 moles phthalic anhydride, 2.75 moles ethylene glycol and 8.25 moles diethylene glycol, was charged into a 2-inch outside diameter by 3-inch long aluminum mold and cured 16 hours at 50° C. Upon removal from the mold, and after cooling, the resultant charge detonated completely with a No. 6 E.B. cap.

EXAMPLE 6

Preparation of explosive casing

A mixture of 65% by weight cyclonite and 35% by weight of a styrene-modified polyester (containing 1% methyl ethyl ketone peroxide and ½% of cobalt naphthenate), where the styrene-polyester was composed of 30% styrene and 70% of the reaction product of 7 moles maleic anhydride, 1.5 moles phthalic anhydride, 1.5 moles adipic acid, 5.5 moles ethylene glycol, 5.5 moles diethylene glycol, was charged into a 3-inch outside diameter, 1½ inch inside diameter by 3-inch long aluminum mold and cured 4 hours at 25° C. Upon removal from the mold, the case was loaded with 50/50 pentolite and detonated with a No. 8 E.B. cap. The case detonated completely.

EXAMPLE 7

Preparation of explosive charge

A mixture of 60% by weight cyclonite and 40% by weight of a mixture composed of 84% ethyl methacrylate monomer, 15% nitrocellulose (½ sec. viscosity) and 1% benzoyl peroxide, was cast into a glass test tube and cured at 50° C. The resultant material was hard and strong and could be detonated completely with a No. 8 E.B. cap.

It will be noted from the above examples that the explosive compositions of this invention may be varied widely to fit specific uses. It is well known that the properties of synthetic addition polymers employed in the invention can be varied within wide limits depending on the extensive range of originating materials available and the conditions of reaction. However, it was quite unexpected to discover that these difficultly combustible materials in combination with explosive ingredients would yield efficient explosive compositions. Although it is not intended that the invention shall be limited to any particular theory of operation, it appears that the retention of the explosive material in dispersed or particulate form throughout the composition imparts properties not otherwise attainable. This applies to propellant explosives, initiating explosives, and high explosives. In accordance with the present invention such explosives have improved thermal stability. This is important since it is sometimes necessary to submit explosives to high temperature conditions. For example, explosives when used as propellants in conjunction with oil well perforator guns are frequently subjected to high temperature zones where premature ignition would damage the casing wall or decline in propulsive strength would cause malfunctioning.

Moreover, high explosives are likewise subjected to conditions of high temperature such as those caused by underground fires in the vicinity of a borehole blasting operation or in the shooting of deep oil wells. It is appreciated that since the polymerization product encases the distinct particles of explosive that a certain degree of insulation relative to thermal conditions exists. Such a condition would indicate that combustion of the propellant explosives and detonation of the high explosives or initiating devices employing the composition would not be satisfactory. However, quite to the contrary it was found that explosives ranging from combustible types to detonative types could be produced satisfactorily. It is believed that having the explosive in distinct particles and encased within the polymerization product enhances the chemical transformation of these particles whether produced by heat or shock.

The compositions of the present invention may be produced by intimately and uniformly mixing polymerizable vinyl type materials with nonaromatic explosive material selected from the group consisting of azides, organic nitrates and organic nitramines and subsequently curing the same. The materials may first be mixed and cast in a suitable mold, added separately, or added together and mixed in the mold. Generally, the explosive composition thus produced will be removed from the mold in the shape of its intended use. In some instances, however, the mold may comprise the warhead of high-explosive ammunition or the like in which the explosive composition is retained. In other instances, where propellant-type explosive is desired, the composition may constitute an individual charge or it may be subsequently granulated after polymerization. In still other instances, the explosive composition may be cast or extruded on an endless belt and conveyed to a curing zone. This procedure is desirable in the formation of thin sheets or sections of rigid or flexible product, particularly where a considerable length is desired.

The polymerization products utilized in accordance with this invention may be polymers, copolymers, cross-linked addition polymers or mixtures thereof. The consistency of the polymerizable materials may vary from very fluid to pasty and the viscosity of these materials may be varied by mixture or by partial polymerization before use. Thus, polymeric methyl methacrylate may be dissolved in monomeric methyl methacrylate and the explosive material added. Generally, the materials for the polymerization reaction will be nonexplosive, although explosive monomeric materials are operable. Moreover, soluble explosive material may be added to the nonexplosive materials for the polymerization reaction providing that the material itself and the amount present do not inhibit the polymerization reaction. An example of such material is nitrocellulose which has shown satisfactory results when used in amounts as high as 65% by weight in solution with the nonexplosive material, such as methyl methacrylate, employed for the polymerization reaction. Similarly, other soluble explosive materials may be incorporated to provide fuel for the explosive composition as well as adjustment of the viscosity. Plasticizers may be added to modify the properties of the matrix if desired. Non-explosive plasticizers include triacetin, alkyl phthalates such as dibutyl- and diethyl-phthalate, long chain adipates, and sebacates such as dihexyl sebacate and didecyl adipate. Explosive plasticizers such as the liquid explosive nitric esters also may be employed.

In general, the polymerizable materials employed in preparing the compositions of the invention are monomeric or partially polymerized vinyl materials which readily form linear or cross-linked type polymers in the presence of a polymerization catalyst and at low temperatures. Materials which harden or cure by condensation type reaction are not operable in the invention since in general they require undesirably high temperatures for the reaction and invariably evolve undesirable gaseous or

liquid by-products which adversely affect the physical properties of the final product. Thus, the phenol-formaldehyde, urea-formaldehyde, or melamine type of synthetic resins and the like are excluded from the invention.

More specifically, the operable vinyl type polymerizable materials include the acrylics such as methyl, ethyl and butyl acrylate or methacrylate; styrene, styrene-polyesters, acrylonitrile, diallyl phthalate and the like. The acrylics and the styrene-polyesters are preferred. In general, the styrene-polyesters will contain from about 30-70% styrene and from about 70-30% polyester. Preferred polyesters are the reaction products of ethylene glycol, diethylene glycol and propylene glycol with maleic, fumaric or phthalic acid. Cross-linking agents for the styrene such as diallyl phthalate or triallyl cyanurate may also be included. Commercially available styrene polyesters which give excellent results are: a styrene modified polyester resin sold under the trade-mark Stypol 107-E, a polyester resin of the copolymer type sold under the trade-mark Selectron 5003, a cross-linked polyester resin sold under the trade-mark Vibrin 121. The commercial products often contain a polymerization accelerator such as cobalt naphthenate, which is usually present in an amount of less than 1% by weight. All these materials may be polymerized in situ and have excellent casting characteristics with a cure rate adjustable over a wide range of temperature and time. Moreover, the polymerization reaction may be carried out under conditions of temperature and catalysis with temperatures from about 20° C. to not more than about 100° C. and with peroxidic catalysts such as benzoyl peroxide, lauroyl peroxide, methyl ethyl ketone peroxide and tertiary butyl hydroperoxide or catalysts such as di-tert-butyl diperphthalate and tert-butyl perbenzoate. The peroxidic catalysts are preferred, and although the catalysts may be used in amount up to about 10%, the preferred amount is ordinarily about 1 to 5% by weight of the monomer being utilized. The cure time of these materials will vary from a few minutes to several days and the amount and type of catalyst may be selected to give the cure time desired for the particular resin.

As indicated, the explosive material which is admixed with the polymerizable vinyl material to form the polymerization products of the invention will be chosen from nonaromatic explosives selected from the group consisting of azides, organic nitrates and organic nitramines and will preferably be selected from the group consisting of non-aromatic crystalline high explosives such as ethylene dinitramine, methylene dinitramine, cyclotrimethylenetrinitramine (cyclonite), diethanolnitramine dinitrate, pentaerythritol tetranitrate, lead azide, silver azide, nitrolactose, sucrose octanitrate, lactose octanitrate and mannitol hexanitrate. Nitrocellulose in fibrous or filament form or in solution may also be employed. When it is desired to incorporate a liquid explosive in the composition, nitroglycerin or other liquid nitric ester may be employed. Aromatic explosive compounds are not operable in the invention since the aromatic nucleus inhibits polymerization of the vinyl material and prevents satisfactory consolidation of the charge. The amount of explosive material which may be present is subject to a wide range depending on the characteristics desired of the composition. The amount will range from about 50 to about 85%, and preferably from about 60 to about 80%, by weight of the explosive composition. With low amounts of explosive material present, very hard or very flexible compositions may be obtained which are difficultly detonatable and combustible. With high amounts of explosive material present, compositions may be obtained which are easily detonatable and combustible. The particle size of the solid explosive preferably should be such that substantially all passes through a 40-mesh screen although the particle size may be varied over wide limits. In general, the sensitivity of solid explosives to initiation is increased by lowering the particle size. Therefore, to increase sensi-

tivity to blasting caps or equivalent initiating means, sensitivity will be raised by decreasing the particle size of the solid explosive. Burning speed of the deflagrating compositions is increased by decreasing particle size of the explosive component. The viscosity of the products to be polymerized will also govern to a considerable extent the particle size of the explosive so that uniform dispersion and adequate wetting are obtained.

It will be evident to those skilled in the art that the auxiliary agents customarily employed in the molding of organic compounds may be incorporated in the explosive compositions of this invention to the extent that the polymerization reaction is not unduly inhibited and the composition is not impaired in respect to its desired function. Such auxiliary agents may include reinforcing agents such as fiberglass, fillers, pigments, dyes, cellulose derivatives, natural resins, and the like. These agents may be employed to obtain certain desired physical and/or chemical characteristics in the intermediate as well as the end product.

It will be seen, therefore, that this invention may be carried out by the use of various modifications and changes without departing from its spirit and scope.

The explosive compositions of this invention may be used in applications such as initiating devices, commercial blasting explosives, military explosives, propellants, gas generating charges, shaped charges, and fuses including ordinary and detonating types.

The advantages of the invention are numerous and include elimination of the necessity for containers, good thermal stability, good water resistance, controlled degrees of sensitiveness, and economies in any use where the properties of the explosive composition permit the elimination of supporting components entirely, or a reduction in the structural requirement of such components, and provide an improved method for charging an explosive container including flexible tubing for fuses.

This application is a continuation-in-part of application Serial No. 538,788 filed October 5, 1955, now abandoned, which in turn is a continuation-in-part of application Serial No. 25,993 filed May 8, 1948, now abandoned.

What I claim and desire to protect by Letters Patent is:

1. As a new article of manufacture, an explosive unitary mass of a fissure-free synthetic waterproof, self-sustaining, resinous polymerization product which is the polymerized reaction product consisting essentially of from about 50 to about 85% by weight of particulate nonaromatic crystalline high explosive of the group consisting of ethylene dinitramine, methylene dinitramine, cyclotrimethylenetrinitramine, diethanolnitramine dinitrate, pentaerythritol tetranitrate, lead azide, silver azide, nitrolactose, sucrose octanitrate, lactose octanitrate and mannitol hexanitrate in intimate and uniform mixture with from about 15 to about 50% by weight of catalyzed vinyl material of the group consisting of methyl acrylate, ethyl acrylate, butyl acrylate, methyl methacrylate, ethyl methacrylate, butyl methacrylate, styrene, styrene-polyester, acrylonitrile and diallyl phthalate, the reaction mass being shaped and polymerized in situ at a temperature from about 20 to about 100° C. to yield said polymerized reaction product.

2. As a new article of manufacture, an explosive unitary mass of a fissure-free synthetic waterproof, self-sustaining, resinous polymerization product which is the polymerized reaction product consisting essentially of from about 60 to about 80% by weight of particulate nonaromatic crystalline high explosive of the group consisting of ethylene dinitramine, methylene dinitramine, cyclotrimethylenetrinitramine, diethanolnitramine dinitrate, pentaerythritol tetranitrate, lead azide, silver azide, nitrolactose, sucrose octanitrate, lactose octanitrate and mannitol hexanitrate in intimate and uniform mixture with from about 20 to about 40% by weight of catalyzed vinyl material of the group consisting of methyl acrylate, ethyl acrylate, butyl acrylate, methyl methacrylate, ethyl

methacrylate, butyl methacrylate, styrene, styrene-polyester, acrylonitrile and diallyl phthalate, the reaction mass being shaped and polymerized in situ at a temperature from about 20 to about 100° C. to yield said polymerized reaction product.

3. As a new article of manufacture, an explosive unitary mass of a fissure-free synthetic waterproof, self-sustaining, resinous polymerization product which is the polymerized reaction product consisting essentially of from about 60 to about 80% by weight of cyclotrimethylenetrinitramine in intimate and uniform mixture with from about 20 to about 40% by weight of catalyzed diallyl phthalate, the reaction mass being shaped and polymerized in situ at a temperature from about 20 to about 100° C. to yield said polymerized reaction product.

4. As a new article of manufacture, an explosive unitary mass of a fissure-free synthetic waterproof, self-sustaining, resinous polymerization product which is the polymerized reaction product consisting essentially of from about 60 to about 80% by weight of pentaerythritol tetranitrate in intimate and uniform mixture with from about 20 to about 40% by weight of catalyzed methylmethacrylate, the reaction mass being shaped and polymerized in situ at a temperature from about 20 to about 100° C. to yield said polymerized reaction product.

5. As a new article of manufacture, an explosive unitary mass of a fissure-free synthetic waterproof, self-sustaining, resinous polymerization product which is the polymerized reaction product consisting essentially of from about 60 to about 80% by weight of pentaerythritol tetranitrate in intimate and uniform mixture with from about 20 to about 40% by weight of catalyzed styrene-

polyester, the reaction mass being shaped and polymerized in situ at a temperature from about 20 to about 100° C. to yield said polymerized reaction product.

6. As a new article of manufacture, an explosive unitary mass of a fissure-free synthetic waterproof, self-sustaining, resinous polymerization product which is the polymerized reaction product consisting essentially of from about 60 to about 80% by weight of cyclotrimethylenetrinitramine in intimate and uniform mixture with from about 20 to about 40% by weight of catalyzed styrene-polyester, the reaction mass being shaped and polymerized in situ at a temperature from about 20 to about 100° C. to yield said polymerized reaction product.

7. As a new article of manufacture, an explosive unitary mass of a fissure-free synthetic waterproof, self-sustaining, resinous polymerization product which is the polymerized reaction product consisting essentially of from about 60 to about 80% by weight of cyclotrimethylenetrinitramine in intimate and uniform mixture with from about 20 to about 40% by weight of catalyzed ethyl methacrylate, the reaction mass being shaped and polymerized in situ at a temperature from about 20 to about 100° C. to yield said polymerized reaction product.
